ELECTRONIC FLASH UNIT

Wilfried Holtje and Claus Prochnow, Braunschweig, Germany, assignors to Rollei-Werke Franke & Heidecke, Braunschweig, Germany

Filed Jan. 15, 1974, Ser. No. 433,532

Claims priority, application Germany Aug. 13, 1973;
Aug. 20, 1973

Term of patent 14 years

Int. Cl. D16—05

U.S. Cl. D61—1 F

FIG. 3

FIG. 1

FIG. 2

FIG. 4

FIG. 5

FIG. 6

FIG. 9

FIG. 7

FIG. 8

FIG. 10

FIG. 11

FIG. 12

FIG. 1 is a front elevational view of an electronic flash unit, showing our new design;

FIG. 2 is a right side elevational view thereof;

FIG. 3 is a top plan view thereof;

FIG. 4 is a bottom view thereof;

FIG. 5 is a rear elevational view thereof;

FIG. 6 is a left side elevational view thereof showing lamp member in a tilted condition;

FIG. 7 is a front elevational view of a modified form of the design shown in FIG. 1;

FIG. 8 is a right side elevational view thereof;

FIG. 9 is a top plan view thereof;

FIG. 10 is a bottom view thereof;

FIG. 11 is a rear elevational view thereof; and

FIG. 12 is a left side elevational view thereof, showing the lamp member in a tilted condition.

We claim:

The ornamental design for an electronic flash unit, substantially as shown and described.
